FOOT HOLDER

Filed June 13, 1932

UNITED STATES PATENT OFFICE

JOHN FERD ROOS, OF LEWISTON, IDAHO

FOOT HOLDER

Application filed June 13, 1932. Serial No. 616,998.

My present invention relates to an improved foot holder or foot rest, which, while designed especially as a golf accessory, for use by a golf player or beginner, in learning and maintaining the correct stance, is also adapted for use by ball players, and players engaged in other sports.

As is well known, the correct stance, in the game of golf, requires that the advanced or forward foot of the player be disposed with its longer axis on a line substantially perpendicular to or at right angles to the line of flight of the ball as it is addressed; or perpendicular to the line extending between the ball and the hole. With the advanced foot of the player in this position the leg is properly braced at the instant the driver or the iron connects with the ball, and this bracing of the foot and leg insures balance for the player, power, accuracy, and direction in connecting with the ball, and an easy and correct follow through after the ball has been struck.

By the utilization of the foot holder or foot rest of my invention, as a guide for the foot of the player, the foot is prevented from slipping or twisting, the proper stance is maintained, and the correct form may readily be learned, after practice, and thereafter maintained as a matter of habit. The foot rest of my invention may be reversed or inverted for use by either right-hand or left-hand players, and it is portable in order that it may be carried in the golf bag, or otherwise, and be readily accessible for use when required. The foot rest may be employed in practice, or during a game, and it may readily and quickly be set up on the ground for use, and with equal facility may be picked up and restored to the golf bag for future use.

The invention consists in certain novel combinations and arrangements of parts involved in the construction of the foot rest as will hereinafter be more fully set forth and claimed. In the accompanying drawing I have illustrated one complete example of the physical embodiment of my invention wherein the parts are combined and arranged according to one mode I have thus far devised

for the practical application of the principles of my invention.

Figure 1 is a perspective view of a foot rest, guide, or holder, embodying my invention, in position for use, and as seen from the outer or front side.

Figure 2 is a sectional detail view as at line 2-2 of Figure 3.

Figure 3 is a plan view of the foot rest, with its pegs folded to inactive position.

Figure 4 is a perspective view of one of the several socket-bushings employed in the holder.

In carrying out my invention I use the device 1, which may be fashioned from any suitable material for the purpose, and is provided with opposed flat, parallel faces, either of which is adapted to rest upon the ground, and the rear side of the rest is fashioned with a recess 2 that is adapted to receive against its wall the left front and side portion of the toe of the shoe of the left foot of a right-hand player, as in Figure 1. Or the rest may be turned over on the ground, for a left-hand player, who places the right front and side portion of his right shoe against the walls of the recess. The rest is thus of angular shape, or at least one side of the rest is fashioned with a recess having angular walls against which the shoe of the player is placed, the edge of the sole of the shoe usually contacting with the walls of the recess.

At its ends the rest or block 1 is fashioned with rounded heads 3 and 4, and on the outer side wall of the block opposed notches 5, 5, are fashioned, by means of which the block may be grasped, or which may be used for the application of power from a suitable lever when the block is being removed from its station. In the opposite flat faces of the block pairs of grooves as 6 and 7, and 6' are fashioned extending from the ends toward the central portion of the block, and these grooves are adapted to receive the three pegs, indicated as 8, 8, 8, when the latter are not in use. The three pegs may be located to project from the block and fold in the grooves alternately, from the opposite flat faces of the block, depending on the right-hand or left-hand use of the block or rest,

and these pegs are to be driven or forced, as by foot pressure on the block, into the ground to rigidly hold the block in position for use.

In the opposite ends of the block or rest 5 and at its central portion, holes 9 are fashioned therethrough, and the opposite ends of these holes are enlarged or countersunk, as at 10 to receive liners or metallic bushings 11 arranged in pairs in each hole. The bushings 10 are also enlarged to form cups 12 that fit in the countersinks 10 of the holes, and as seen in Figure 2 the bushings are forced into the holes from opposite sides of the block and firmly imbedded therein. The reduced portion of each bushing is interiorly threaded as 15 at 13, and the wall of each cup is notched or slotted as at 14, the notch or slot being complementary to a groove 6, 6' or 7.

For attaching the foldable pegs 8 to the 20 block, each peg is provided with a screw-shank 15 fashioned with a bifurcated end 16, and the flattened end of the peg is pivoted in this bifurcated end of the screw, as at 17. As indicated in Figures 2 and 3 the grooves 6, 7, 25 are of sufficient length to accommodate the full length of the pin or peg when the latter is folded on its hinge or pivot, and the pivotal joint between the pin or peg and its screw shank may have sufficient frictional contact 30 between these parts to hold the peg in angular position. The hinged peg is opened out on its hinge joint similar to a knife blade, and when the pegs have been opened to extended 35 position as in Figure 1, the foot rest is placed in position on the ground, with the points of the pegs slightly penetrating the sod. After the foot rest has been thus positioned, if the ground is soft, the pegs may be forced into the ground by hand, or if the ground is harder, the foot may be placed on the top face 40 of the block and by pressure thereon, the pegs are forced into the ground in order that the foot holder may be employed for the performance of its functions.

45 When changing the device from a right-

hand use to a left-hand use, the pegs are unscrewed, as from the position of Figure 2, and then the screw shanks are inserted in the top bushings and threaded therein to firmly anchor the foldable pegs or pins. 70

To insure the proper stance, the toe of the golfer's shoe is placed in the recess 2 of the foot rest and the latter forms a guide and brace for the foot. Many golf players, on the back swing, slightly turn the foot inwardly, and in the event of such movement the rounded end 3 (or the rounded end 4) of the rest permits an uninterrupted, and easy turn of the foot without likelihood of the golfer losing his balance. 75 80

Having thus fully described my invention, what I claim as new and desire to secure by Letters Patent is:—

1. A foot-holder of the character described having grooves in its face, a plurality of foldable pins hinged and anchored in the holder and adapted when folded to lie in said grooves. 85

2. A foot holder as described having a threaded bushing therein, a shank threaded in said bushing, and a foldable peg hinged on said shank. 90

3. A foot holder having a groove in its face, a threaded bushing fixed in said holder and an enlarged cup integral with the bushing and formed with a slot complementary to said groove, a screw shank threaded in said bushing and having a bifurcated end in the cup, and a foldable peg pivoted in said bifurcated end. 95

4. A footholder for golfer's use comprising an angular block adapted to rest upon the ground and having a lateral recess conforming to the shape of the toe of a shoe, a plurality of foldable pegs, sockets mounted on said block, and co-acting means on the pegs and sockets for retaining the pegs in the sockets. 100 105
